UNITED STATES PATENT OFFICE

RHEUEL H. FREDERICK, OF IRVINGTON, NEW JERSEY, ASSIGNOR TO AMES PUMP COMPANY, INC., OF NEW YORK, N. Y., A CORPORATION OF NEW YORK

CENTRIFUGAL PUMP

Application filed March 31, 1928. Serial No. 266,149.

This invention relates to centrifugal pumps; and its primary object is to provide a pump of single and efficient construction whereby variable capacity and pressure can be attained, that is to say, the capacity can be varied within wide limits and any predetermined capacity can be maintained, and the pressure automatically adjusts itself to the prescribed capacity and remains constant and positive during the operation of the pump, all without recourse to structural alteration of the pump or variation of the speed of the rotor.

Another object of my invention is to provide a unitary centrifugal pump wherein the pressure and velocity of the liquid are progressively varied in its passage from the impeller chamber to the final discharge outlet in a manner to build up the head, thus attaining with a single pump high pressures which, in centrifugal pumps as heretofore constructed, would necessitate the employment of from four to six stages, and thus also minimizing weight and floor space and economizing in manufacturing and installation costs.

With these and other objects in view my invention comprises novel features of construction and combinations of parts which will be hereinafter described; the scope of the invention then being defined in the appended claims.

In the annexed drawings—

Figure 1 is a side elevation of a centrifugal pump embodying the principle of my invention.

Fig. 2 is an end elevation of the pump.

Fig. 3 is a transverse vertical section through the pump, as on the line 3—3 of Fig. 1.

Fig. 4 is a horizontal section, as on the line 4—4 of Fig. 1.

Fig. 5 is a vertical section, partly in elevation, as on the lines 5—5 of Figs. 2 and 3.

Fig. 6 is a similar section, as on the line 6—6 of Fig. 3.

Fig. 7 is a sectional development through portions of the casing and rotor, as on the line 7—7 of Fig. 5, showing lateral volute passages and their Venturi outlets leading to annular velocity chambers, and showing also

adjustable valves for regulating the flow of the liquid from the volute passages to the outlets.

Fig. 8 is a similar development through a portion of the casing and of the annular structure in which the velocity chambers are formed, as on the line 8—8 of Fig. 5, showing the lateral passages in said structure which connect the inner with the outer chambers, the rotor vanes for the respective chambers being indicated.

Fig. 9 is a transverse section through the lateral passages connecting the velocity chambers, as on the line 9—9 of Fig. 5.

Fig. 10 is a sectional detail adjacent the discharge outlet of the pump, showing the mid rib which supports the annular structure and separates the velocity chambers at their points of discharge.

The pump casing illustrated in the drawings comprises complementary upper and lower sections 11, 12, respectively, of appropriate size and form to provide a series of intercommunicating chambers and passages, including a suction or inlet chamber 13, a circular rotor chamber 14 and a discharge outlet 15, said suction chamber and outlet being formed in the lower section 12, and said rotor chamber being partially formed in each section and being adapted to receive and support a circumferential structure constituting a series of annular velocity chambers connecting the rotor chamber with the outlet, as will hereinafter appear.

Mounted in the chamber 14 is a rotor including a discal body 16 which, in the form illustrated, divides the chamber 14 into two separate chambers A, B. This body has a central hub 17 which is rotatable in the walls 100 of the casing between the rotor chamber and the suction chamber, and is provided at its respective ends with inlet eyes or passages 101. The hub is fixed by means of nuts 18 and lock washers 19 to a power-driven shaft 20 which extends centrally through the rotor chamber and is mounted in suitable bearings supported at the respective sides of the casing. The bearing supports may be cast integral with the lower section of the casing, or be mounted on uprights rising from a bed

plate, as desired, while the joint between the two sections of the casing extends in a horizontal plane coincident with the axis of the shaft. Removable stuffing boxes 21 are suitably supported in the outer walls of the casing at the respective sides of the suction chamber 13. The stuffing boxes contain packing rings 22 and spaced liquid seal rings 23, and the body of each box is drilled, as at 24, to afford a liquid supply duct leading to the space between the rings. Tubes 25, which connect the ducts 24 with the adjacent chambers A, B, ensure the supply of liquid under pressure from these chambers to the sealing rings; and glands 26, which are inserted in the outer ends of the stuffing boxes, keep the packing rings in close contact with the shaft 20.

To ensure a tight seal at the rotor hub and thereby reduce the liability of leakage of the liquid from the chambers A, B to the suction chamber 13, packing rings 27 of general H-cross-section are screwed or otherwise fastened on the respective ends of the hub 17, and complementary case rings 28, 29 are fitted on the respective sides of each of the rings 27, so as to mesh with yet permit the free running of the interposed ring. The case ring 28 at the suction chamber side is of general E-form in cross-section with an outer peripheral flange 30, which ring is fitted to the outer side of the ring 27 so as to register with and embrace the latter, the upper member, including its flange, being tightly seated in the case ring bore of the casing wall, and the wall of this bore being formed with an annular recess 31 to receive the flange. The case ring 29 at the impeller chamber side is of general U-form in cross-section with an outer peripheral flange 32, which ring is fitted to the inner side of the adjacent ring 27, with the upper member, including its flange, tightly seated in the case ring bore of the casing in close contact with the complementary case ring 28. By the interlocking construction just described a multiplicity of contacting joint surfaces whereof the minimum area is subjected to the maximum pressure is provided, thus ensuring an efficient seal as previously mentioned.

The rotor body 16, hereinbefore referred to, has formed on its respective sides centrifugal impellers comprising annular walls or shrouds 33 between which and the adjacent faces of the discal body are cast two series of impeller vanes 34. The annular spaces in which the vanes are contained communicate with the inlet eyes or passages in the hub of the rotor, and the outer portions of such spaces open directly into the adjacent chambers A, B. By this construction is provided a rotor having on its respective sides centrifugal impellers to which the fluid from the suction chamber is delivered by virtue of the vacuum created in the latter by the kinetic

energy imparted to the currents of water flowing through the rapidly rotating impellers.

The discal body 16 extends outwardly beyond the impeller vanes 34 and is provided on each side, at its peripheral margin, with two circular series of vanes 36, 37 which are concentric to each other and to the discal body and are at right angles to the latter and are forwardly pitched in relation to the direction of rotation of the impeller vanes 34.

The outer portion of the discal body, including the marginal vanes 36, 37 on the respective sides thereof, rotate in annular velocity chambers 38, 39 which are arranged in the same vertical planes as the respective sets of impeller vanes 34, the inner velocity chamber 38 being in communication with the adjacent chamber A or B, and with the other velocity chamber 39, and the latter chamber being in communication with the discharge outlet 15 as will be hereinafter described.

The velocity chambers 38, 39 are preferably constituted by complementary rings 40 of general E-form in cross-section which are oppositely-disposed with their flanges in close contact, and which rings are tightly fitted between the walls 100 of the chamber 14 adjacent its circumference. Thus four annular velocity chambers are provided, two on each side for co-operation with the adjacent impeller of the rotor. The inner flanges, 41, and the intermediate flanges, 42, of the rings 40 are formed with concentric tongues 43, and the sides of the discal body are formed with corresponding grooves which slidably receive the respective tongues when the rings and the rotor are assembled within the casing, thus permitting the free rotation of the marginal portions of the discal body and the vanes 36, 37 within the velocity chambers 38, 39.

Each of the impeller chambers (A, B) merges in a lateral volute passage 44 formed in the wall 100 of the casing whose sides are entirely enclosed by walls surrounding said passage, which passage leads to an eduction opening 45 for the liquid which is delivered to the chamber by the rapidly rotating impeller. This opening is at one end of a curved passage 46 also formed in the wall 100 of the casing, which passage leads to the adjacent velocity chamber 38. The ring 40 is appropriately shaped to afford communication of the passage 46 tangentially with the velocity chamber, as seen in Figs. 5 and 7, and, therefore, the liquid which is discharged by centrifugal force from the periphery of the impeller is caused to flow into the chamber 38 wherein it is subjected to the propulsive action of the vanes 36 during their rapid rotation. By this arrangement of the passage 46 with relation to the volute passage and the velocity chamber the con-

tinuity of the latter is preserved and the liquid is discharged thereinto and to the path of the vanes with the minimum friction and without shock losses. The eduction opening 45 has therein a Venturi tube 47, with the inlet to which co-operates a tapering valve stem 48 which is adjustably mounted in the front wall of the casing and in axial alignment with the Venturi tube. In the present instance the valve stem is threaded and screwed into and through a stuffing box 49 supported in a suitably perforated boss 50 on the casing, and hence by properly turning the valve stem to adjust its tapered end in relation to the mouth of the Venturi tube, the intake capacity of the latter can be nicely regulated at will and a predetermined capacity be maintained.

Each of the inner velocity chambers 38 is provided adjacent the discharge outlet 15 with an egress passage 51 whose sides are entirely enclosed by walls surrounding said passage and which leads to and merges tangentially in the adjacent outer velocity chamber 39, and each chamber 39 is provided with an egress passage 52 which leads to and merges tangentially in the discharge outlet 15, said passages 51, 52 being formed in the ring sections laterally of the reflective chambers, and the walls of each passage diverging from its receiving to its delivery end, similarly to a Venturi outlet portion. (See Figs. 5, 6, 7, 8 and 10.) Since the passages 51, 52 extend laterally of the respective velocity chambers, the continuity of said chambers is preserved and the liquid which is discharged from each adjacent chamber flows thence without interference with the vanes of such chamber, thus eliminating shock losses to the traveling liquid.

The lower section of the casing where the velocity chambers 39 communicate with the discharge outlet 15 is formed with a mid rib 53 which affords a closed peripheral support for the ring structure and also separates the two adjacent velocity chambers 39 at their points of discharge. (See Figs. 5 and 10).

The cycle of the flow of liquid through the pump hereinbefore described and the changes of velocities and pressures of the liquid in order to build up the head, are as follows: The liquid in velocity form enters the suction chamber 13, flows to and through the eyes of the rapidly rotating impellers, and is taken up by the impeller vanes. Thence the liquid in velocity and pressure form flows through the spaces between the impeller blades, into the chambers A, B, and through the volute passages 44, whence it is discharged through the Venturi tubes; it being noted that by suitably adjusting the valve stems 48 to vary the size of the inlets to the Venturi tubes, the capacity of the pump can be nicely regulated to meet specific requirements. These tubes by virtue of their contracted areas

change the pressure energy of the fluid into velocity or kinetic energy, whereupon the liquid, escaping such areas, flows in pressure and velocity form into the annular velocity chambers 38 wherein the forwardly pitched 70 highly rotating vanes 36 increase the velocity of the liquid therethrough. When the liquid reaches the passages 51 its velocity is reduced to pressure by the effect of the gradually diverging passages 51, and hence the liquid 75 flows into the annular chambers 39 in pressure and velocity form. The forwardly pitched vanes, rotating at high speed in the chambers 39, increase the velocity of the liquid therethrough, and this higher velocity when the 80 liquid reaches the passages 52 is reduced to pressure by the diverging walls of the latter, preparatory to the discharge of the liquid through the final outlet.

From the foregoing described construction 85 it will be seen that a single unitary pump of variable capacity and pressure, at uniform motor speed, is produced; the capacity being regulable by proper manipulation of the valves 48 and the resultant pressure being determined by the horsepower of the motor. Thus, for example, the pump can be efficiently employed without any constructive change for a range of from, say, 100 to 600 pounds, 90 and from, say, 50 to 100 gallons per minute at 1750 R. P. M., the only requirement being the provision of increased horsepower for the increased pressure irrespective of the adjusted capacity.

Assuming the pump be installed for working conditions of three hundred pounds pressure and fifty gallons per minute at 1750 R. P. M., and it be desired to increase or decrease the capacity of the pump, the valves 100 are adjusted to deliver the desired capacity, but the pressure will remain the same, viz.: three hundred pounds, since changing the volume does not change the pressure. Assuming it be desired at any time to increase 105 the pressure at 1750 R. P. M., it is merely necessary to employ a motor of horsepower effective to attain the increased pressure at 1750 R. P. M.

The pump is positive in pressure and is 110 effective to pump against a range of from one hundred to six hundred pounds pressure, for the reason that the edges of the vanes traveling in the velocity chambers hold the contained column of liquid until it produces 115 the desired pressure.

Since the variable capacity and pressure conditions are accomplished with one fixed impeller diameter and a constant speed, duplicate pumps may be installed and adjusted; 120 one for, say, 50 gallons per minute and 50 lbs. pressure at a constant speed of 1750 R. P. M., and the other for 75 gallons per minute and 100 lbs. pressure at 1750 R. P. M., the only requirement being the provision of 130

increased horsepower for the larger duty, as previously mentioned.

In centrifugal pumps of previous construction any inaccuracy in the design thereof with respect to the pressure or capacity in a given case, on account of frictional resistances, necessitates a change in the speed or in the diameter of the impeller, whereas with a pump embodying my invention the pump will automatically adjust itself to differential pressure conditions existing after installation, and if it be necessary or desirable to change the capacity of the pump this can be readily effected by adjusting the regulating valves as previously described.

While I have illustrated and described my invention as embodied in a pump having an integral double impeller, it is to be understood that in accordance with the principle of my invention a single impeller may be employed, and that the velocity chambers may be increased or decreased in number to meet particular requirements of service. Also that in other respects the pump may be structurally modified within the fair spirit of the invention and the scope of the appended claims.

I claim—

1. A centrifugal pump comprising a suction chamber having a liquid inlet, an impeller chamber having an outlet passage, an annular velocity chamber encircling the impeller chamber and in communication at its receiving end with said outlet passage, means for varying the capacity of said outlet passage, and a rotor mounted to rotate in the impeller chamber and velocity chamber, said rotor comprising a body having an impeller within the impeller chamber, vanes within the velocity chamber, and a liquid inlet to the impeller from the suction chamber.

2. A centrifugal pump comprising a suction chamber having a liquid inlet, an impeller chamber having an outlet passage, including a venturi, an annular velocity chamber encircling the impeller chamber and in communication with said outlet passage, means for varying the capacity of the venturi, and a rotor mounted to rotate in the impeller chamber and velocity chamber, said rotor comprising a body having an impeller within the impeller chamber, vanes within the velocity chamber, and a liquid inlet between the impeller and the suction chamber.

3. A centrifugal pump comprising a suction chamber having a liquid inlet, an impeller chamber having an outlet passage, including a venturi, a ring structure encircling the impeller chamber and providing a velocity chamber in communication with said outlet passage, a valve stem adjustable axially of the venturi for varying the capacity of the venturi, and a rotor mounted to rotate in the impeller chamber and veloc-

ity chamber, said rotor comprising a body having an impeller within the impeller chamber, vanes within the velocity chamber, and a liquid inlet to the impeller from the suction chamber.

4. A centrifugal pump comprising a suction chamber having a liquid inlet, an impeller chamber having an outlet passage, a plurality of succeeding concentric velocity chambers encircling the impeller chamber, the first velocity chamber being in communication at its receiving end with said passage, means for varying the capacity of said outlet passage, a diverging passage leading from said first velocity chamber to the succeeding velocity chamber, and a rotor mounted to rotate in the impeller chamber and velocity chambers, said rotor comprising a body having an impeller within the impeller chamber, vanes within the respective velocity chambers, and a liquid inlet to the impeller from the suction chamber.

5. A centrifugal pump comprising a suction chamber having a liquid inlet, an impeller chamber having an outlet passage, including a venturi, an adjustable needle valve cooperating with the venturi, a plurality of concentric velocity chambers encircling the impeller chamber, one of said latter chambers being in communication with said outlet passage, a diverging passage leading from the said velocity chamber to the succeeding velocity chamber, and a rotor mounted to rotate in the impeller chamber and velocity chambers, said rotor comprising a body having an impeller within the impeller chamber, vanes within the respective velocity chambers, and an inlet passage between the impeller and the suction chamber.

6. A centrifugal pump comprising a suction chamber having a liquid inlet, an impeller chamber having an outlet passage, including a venturi, a plurality of concentric velocity chambers encircling the impeller chamber, one of said latter chambers being in communication with said outlet passage, means for varying the capacity of said passage, a diverging passage leading from the said velocity chamber to the succeeding velocity chamber, and a rotor mounted to rotate in the impeller chamber and velocity chambers, said rotor comprising a body having an impeller within the impeller chamber, vanes within the respective velocity chambers, and a liquid inlet passage to the impeller from the suction chamber.

7. A centrifugal pump comprising a suction chamber having a liquid inlet, an impeller chamber having two spaced-apart outlet passages, each including a Venturi portion, two series of concentric velocity chambers encircling the impeller chamber, the inner velocity chambers being in communication with the respective outlet passages, means for varying the inlet capacity of the

respective Venturi portions, diverging passages establishing communication between the inner and outer velocity chambers of the respective series, and a rotor mounted to rotate within and partition the impeller chamber and the two series of velocity chambers, said rotor comprising a discal body having impellers on its respective sides within the impeller chamber and having also vanes arranged and adapted to rotate within the respective velocity chambers, and liquid inlets from the suction chamber to the respective impellers.

5 10 15 20 25 30 35 40 45 50 55 60 65

8. A centrifugal pump embodying an impeller chamber, annular velocity chambers, and a rotor body having impeller vanes rotatable within the impeller chamber and having also marginal propulsion vanes rotatable within the velocity chambers, said velocity chambers being constituted by complementary channelled ring sections between which the body of the rotor extends, the contiguous surfaces of the rotor and ring sections having annular grooves and tongues in slidably registry with each other.

9. A centrifugal pump comprising a casing formed of two sections connected to each other, a shaft rotatably mounted in the casing, a rotor connected to the shaft, a ring on each side of the rotor within the casing, an impeller chamber on each side of the rotor between the walls of the casing and the inner periphery of one of the rings, a velocity chamber in each ring encircling one of the impeller chambers, an impeller on the rotor in each impeller chamber, vanes on the rotor in each velocity chamber, an inlet to each impeller chamber, a passage from each impeller chamber to one of the velocity chambers, a portion of each of said passages being entirely surrounded by side walls, means for varying the capacity of each of said passages, an outlet from the casing, and an outlet from each of said velocity chambers to the outlet from the casing.

10. A centrifugal pump comprising a casing formed of two sections connected to each other, a shaft rotatably mounted in the casing, a rotor connected to the shaft, a ring on each side of the rotor within the casing, an impeller chamber on each side of the rotor between the walls of the casing and the inner periphery of one of the rings, a velocity chamber in each ring encircling one of the impeller chambers, an inlet to each impeller chamber, a passage from each impeller chamber to one of the velocity chambers, a portion of each of said passages being entirely surrounded by side walls, means for varying the capacity of each of said passages, a second velocity chamber in each ring encircling the first velocity chamber, a passage in each ring from the first velocity chamber to the second velocity chamber, a portion of each of said latter passages being surrounded by side

walls, an impeller on the rotor in each impeller chamber, vanes on the rotor in each velocity chamber, an outlet from the casing, and an outlet from each outer velocity chamber through the walls of a ring to the outlet from the casing.

Signed at New York, in the county and State of New York, this 29th day of March, A. D. 1928.

RHEUEL H. FREDERICK.
